UNITED STATES PATENT OFFICE

GEORGES BEAUMONT, OF MARSEILLE, FRANCE

REFRIGERATOR OF THE ABSORPTION TYPE

Application filed November 22, 1928, Serial No. 321,178, and in France November 9, 1928.

The present invention relates to refrigerators, and more particularly to refrigerators of the absorption type for the production of ice for domestic use. This known kind of refrigerator comprises a generator-absorber and an evaporator-condenser, the upper part of the evaporator-condenser being connected to the lower part of the generator-absorber by a collecting pipe arranged 5 on an axle, by rotation about which axle the refrigerator is enabled to take up three positions corresponding respectively to the operations of clearing, heating and congelation.

These refrigerators have a plurality of conveniences:

1. They involve in general the consumption of a considerable quantity of fuel and a relatively long time for heating.

2. During the evaporation of the gas absorbing solution such as, for example, ammonia,—the so-called rich solution,—small drops of water are carried over with the vapour, as a consequence of which the refrigerating effect is diminished.

3. The gases which return to the generator-absorber for absorption during the congelation form bubbles and these bubbles pass through the weak solution without bursting, so that a counter pressure within the generator-absorber above the absorbing liquid is developed, as a result of which the correct functioning of the apparatus is hindered.

The principal object of the present invention is to provide improvements in this kind of refrigerator for the purpose of avoiding all the above-mentioned inconveniences which render the functioning of the apparatuses uncertain and thus limit their application.

The characteristic feature of the present invention, consists in the increasing of the heating surface by means of tubes which receive the hot gases from the source of heat and convey them to a position adjacent to the centre of the volume of solution to be heated, whereby a considerable economy in the fuel consumption and in the time required for heating is effected. The increase of the heating surface causes the result that small drops of water are carried over with the evaporated gases. In order to render the

gas dry it is necessary to provide means for freeing it from all these drops of water. This result is obtained by means of baffles arranged within the generator-absorber just in front of the outlet opening or collecting pipe 55 leading from the generator-absorber to the evaporator-condenser. In the present case these baffles are constituted by a flat disc arranged at a small distance from the smaller opening of a cone-shaped funnel. In this way not only are the drops of water which are carried off during the evaporation of the rich solution prevented from passing over with the gas into the collecting pipe and thence into the evaporator-condenser, but 60 also, when the apparatus is in the position of congelation the gas which returns to the generator-absorber for absorption, and forms bubbles, cannot pass through the poor solution without the bubbles bursting, so that the 70 production of a counter-pressure in the top of the generator-absorber which might hinder the correct functioning of the refrigerating apparatus is entirely prevented.

A ratchet wheel is also provided on the 75 axle of the collecting pipe, which ratchet wheel co-operates with a pawl on the casing of the refrigerator in such manner as to prevent the possibility of turning the apparatus in the wrong direction in order to bring it 80 into the heating position or congelation position respectively.

A preferred constructional form according to the invention is illustrated by way of example in the accompanying drawings, in 85 which:

Fig. 1 is a longitudinal vertical section of said preferred form of a refrigerating apparatus of the absorption type in the position 90 for heating.

Fig. 2 shows an elevation of the apparatus in the position for congelation.

Fig. 3 is an elevation of the apparatus in the position for clearing.

Fig. 4 is a plan view to Fig. 1, the apparatus being in position for heating.

Fig. 5 is an elevation of a detail, viz. an electrical heating element.

The generator has a cylindrical body 2 (Fig. 1) provided at the end which is to be 100

heated with a central tube 3, extending to about half the length of the generator-absorber and forming a kind of chimney, which discharges into lateral tubes 4 arranged at right angles to the side wall of the body 2, and communicating with the air outside the generator-absorber. The walls of these tubes 3, 4 serve to increase the heating surface of the generator-absorber 2 and to guide the gases coming from a heating means 5 carried by a support 6, towards the central portion of the rich solution 7 contained in the generator-absorber 2.

The central tube 3 is provided with a screw thread 31' which is adapted to co-operate with the screw threaded end 31 of an electrical heating element 32 in known manner. (Fig. 5.) The said heating element 32, when screwed into the central tube 3, will heat the central portion of the rich solution 7, thus very efficiently producing heat within the solution and consequently developing ammonia gas very rapidly. In the position for congelation the tubes 3 and 4 serve as cooling means, inasmuch as a current of fresh air will be automatically produced, owing to the difference of temperature, between the central tube 3 and the tubes 4. The circulation of air which thus arises very quickly produces a vacuum in the interior of the generator-absorber above the weak solution, thus increasing the output of the apparatus.

The inner part of the generator-absorber 2, opposite to the end which is to be heated, is provided with a flat disc 8 of smaller diameter than that of the cylindrical body of the generator-absorber 2. This disc 8 is arranged in close proximity to the opening 9 of a cone-shaped funnel member 10, the base of which is fixed to the side wall of the cylindrical body 2 near to the bottom, the said funnel member covers the sieve-like end 11 of the S-shaped collecting pipe 13 connecting the generator-absorber 2 to the evaporator-condenser 14.

The said evaporator-condenser 14 consists of a tube which is enlarged at its upper part (as shown in Fig. 2), the enlarged part being connected to the collecting pipe 13. The narrower portion of the evaporator-condenser is intended for the reception of the mould. A central tube passes through the evaporator-condenser in known manner from one end to the other. A collar 15 is fixed to the middle of the collecting pipe 14, and carries two horizontal shafts 16, 17 which are mounted at their other ends in supports 18, 19 fixed to the tank or casing 20. The latter is watertight and is provided with a draining pipe 21.

On the shaft 16 a ratchet wheel 22 is fixed, which ratchet wheel co-operates with a pawl 23 fixed to one of the side walls of the casing 20. A handle 24 is provided for the purpose of rotating the apparatus round the shafts 16, 17. The apparatus may be fixed

in each of its three principal positions by means of a retaining member 25 pivotally attached to the casing 20 and adapted to engage with any one of the three rests 26, two of which are arranged on the generator-absorber 2 and one on the evaporator-condenser 14. The apparatus is, of course, made fluid and gas tight.

After a vacuum has been created in the apparatus, the boiler or generator-absorber 2 is charged with an absorbent solution, the constituents of the solution in their proportions in parts by weight being preferably as follows:

12 parts of ammonium acetate.
12½ parts of chloride of calcium.
1 part of distilled water.

This solution has a very high power of absorption without necessitating a high temperature, and being slightly viscous it prevents oxidization of the interior of the apparatus. The mode of operation of the apparatus is as follows:

The generator-absorber is placed in the position indicated in Fig. 1, namely, the heating position, and is maintained in this position by means of the retaining member 25 and the corresponding rest 26 on the side wall of the generator-absorber. The rich solution 7 is very rapidly heated by the passage of the hot gases through the tubes 3 and 4. The ammonia gas thus separates from the liquid and escapes and forms a vapour. The generator-absorber 2 is heated either by means of a fire or burner arranged beneath it on a support 6, or else by means of an electrical heating element 32 which is screwed into the central tube 3.

The ammonia gas ascends in the generator-absorber and impinges on its path first against the disc 8 and then against the outer surface of the cone-shaped funnel 10. These last two members act as baffles and keep the small drops of water and the steam, which ascend with the ammonia gas, back, so that the steam condenses and falls together with the aforesaid small drops down into the solution, whilst the dry ammonia gas passes through the holes of the sieve-like end 11 of the connecting pipe 13. During the heating period the top and side walls of the evaporator-condenser 14 are cooled by means of water issuing from a sprinkler 30. The cooling action thus obtained causes the pure ammonia gas to condense and the evaporator-condenser becomes filled up to a certain height with liquid ammonia. A warning device 35 (a whistle) is provided, which device operates when the apparatus is at a certain definite temperature and pressure, without the escape of ammonia. The sounding of the whistle gives warning (which can be heard at a distance) of the termination of the heating operation, and when this occurs the heating means 5 or the electrical heating

element 32 is withdrawn. The generator-absorber now contains only the absorbent solution, and the evaporator-condenser 14 is filled up with liquified ammonia gas. The 5 retaining member is next withdrawn from the rest 26 and the apparatus is turned by means of the handle 24 into the position for congelation shown in Fig. 2. The turning movement can only be effected in the one 10 direction inasmuch as movement in the opposite direction is prevented by means of the ratchet wheel 22 and the pawl 23, whereby the return of the liquified ammonia from the evaporator-condenser back into the generator-absorber (which would disturb the conge- 15 lation effect) is prevented. When the evaporator-condenser 14 is in the position for congelation the mould 27 containing the liquid to be frozen is attached to it. The said liquid 20 may be allowed to fill even the central tube of the evaporator-condenser 14, whereby the production or output of the apparatus is increased. In this case the said central tube will be closed at its lower part. The genera- 25 tor-absorber 2 is cooled by the passage of air through the tubes 3 and 4, owing to the difference of temperature, a positive cooling draught being thus obtained in addition to the cooling effect produced by the sprinkler 30 arranged above the generator-absorber 2. The liquified ammonia contained in the evaporator-condenser 14 evaporates and returns, owing to the absorption action, through the collecting pipe 13 and its sieve- 35 like end 11 into the weak absorbing liquid. The gas is entirely absorbed by the solution inasmuch as the gas bubbles which escape from the sieve-like end 11 never enter into the upper part of the generator-absorber owing 40 to the fact that they strike upon the baffles constituted by the disc 8 and the funnel 10 and thus burst in the lower portion of the liquid. As a consequence of this the vacuum within the generator-absorber will be main- 45 tained.

If the disc 8 and funnel 10 were not provided the gas bubbles would pass right through the cylinder and would burst within the vacuum of the generator-absorber thereby increasing the pressure and diminishing the absorption power considerably, so that efficient operation of the apparatus as regards output would be impossible. With an apparatus according to the present 55 invention, it is possible to obtain 5 kilogrammes of ice when the atmospheric temperature is 30° C. after a heating operation lasting 40 minutes and a congelation operation lasting 50 minutes.

60 I claim:

1. A refrigerator of the absorption type comprising in combination: a cylindrical generator-absorber; a cylindrical evaporator-condenser arranged with its longitudinal axis 65 parallel to that of said generator-absorber; a

single S-shaped collecting pipe connecting one end face of said generator-absorber with the opposite end face of said evaporator-condenser; a cone-shaped funnel member located adjacent to the end of said generator-absorber 70 at which said collecting pipe enters and covering the end of said collecting pipe within said generator-absorber; a flat disc of smaller diameter than the internal diameter of said generator-absorber arranged at a short distance from the smaller end of said funnel member; and means for rotating the refrigerator about an axis located approximately at the centre of said collecting pipe, substantial- 75 ly as described.

2. A refrigerator of the absorption type as specified in claim 1, wherein said generator-absorber is provided with an axial tube extending within said generator-absorber from that end of the latter which is remote from said collecting pipe, and a plurality of tubes connecting the end of said axial tube with the side wall of said generator-absorber, substan- 80 tially as described.

3. A refrigerator of the absorption type, as 85 specified in claim 1, wherein said collecting pipe is provided with a sieve-like end portion running parallel to the end of said generator-absorber, substantially as described.

4. A refrigerator of the absorption type, as 90 specified in claim 1, wherein said means for rotating the refrigerator comprises: a shaft attached to said collecting pipe and provided with a handle, a ratchet wheel on said shaft, and a pawl co-operating with said ratchet in 95 such manner as only to permit of rotation of said shaft in one direction, substantially as described.

In testimony whereof I have affixed my 100 signature.

GEORGES BEAUMONT.
